1,943,108

MOTOR VEHICLE HEATING SYSTEM

Haldwell S. Colby, Wellsville, N. Y.

Application December 26, 1928
Serial No. 328,542

3 Claims. (Cl. 237—12.3)

The present invention relates to heating arrangements for automobiles and the like, and has particular reference to heating systems for motor busses and motor railway cars.

5 Heating systems of this type utilize the heat of the exhaust gases from the engine, but have the disadvantage that the large sulfur content of the exhaust gases corrodes the heating pipes, thus permitting leakage of exhaust gases into 65
10 the bus and necessitating replacement of the piping. In addition, carbon accumulates within the piping, and must be removed by periodic dismantling and cleaning of the piping sections. The maintenance charge for a heating system of 15 this type has therefore been high.

One object of the present invention is to provide a heating system which will effectively eliminate leakage of exhaust gases into the bus.

Another object is to provide a construction 20 which will not require periodic dismantling and cleaning of the piping sections.

Still another object is the use of a simple, effective heating system which will be strong and sturdy and will withstand the stresses and shocks 25 incident to bus service.

Other objects and advantageous features of the invention will be readily apparent from the following description, in connection with the accompanying drawing showing a plan view of a 30 preferred arrangement of the system.

The motor bus A has the usual chairs 5 therein, indicated in the drawing by means of dotted lines. Beneath each chair 5 is a heating coil 6, having heat-radiating fins 7, and receiving heated 35 air from a common supply main 8 through individual inlet conduits 9. Each heating coil 6 has an outlet 10 exhausting to the atmosphere, but may in certain cases, exhaust into a conduit leading to the air intake of the engine.

40 Air is conducted to the supply main 8 from a cone-shaped receiver 11, preferably stationed in rear of the bus radiator and the radiator fan 18, through a conduit 12, and through an air heater 13 of the continuous regenerative type. 45 The exhaust gases from the engine pass through exhaust pipe 14, and through the preheater 13 into outlet conduit 15 to the atmosphere, or to the usual muffler.

While the rotor 16 of the heater 13 may be 50 operatively connected to the engine shaft if desired, a small impeller 17 is preferably installed in exhaust pipe 14, and rotates the rotor 16 in any desired manner, such as, for example shown in Fig. 4 of U. S. Patent No. 1,638,539. 55 Any other operating mechanism of well known type for slowly turning the rotor 16 may be used.

The described and illustrated arrangement possesses very important advantages. The rotating air heater occupies but little room, is light in

weight, is easily kept clean, and readily withstands the constant vibration and the expansion and contraction which it is subjected to during operation. Although an additional fan in the heater casing or in the conduit 12 may be used to force air through the system, the engine fan will produce a good circulation of air in the 65 illustrated arrangement.

The dissipation of the exhaust gas energy in a heater of the described type, due to rotor resistance, force expended in driving the impeller, and reduction of the temperature and volume of the exhaust gases by absorption of heat, reduces the need for a muffler which can therefore be 70 advantageously omitted. 75

I claim:

1. In a motor-driven vehicle, an internal combustion driving engine, a passenger body, radiators in said passenger body, a regenerative heat exchanger comprising a rotor, means for selectively passing hot exhaust gases from the driving motor through the rotor, and for passing air through the rotor to be heated, means for conducting the heated air from said rotor to said radiators, and means driven by said exhaust gases 80 for rotating said rotor. 85

2. In a motor driven vehicle, an internal combustion driving engine, a passenger body, radiators in said passenger body, a regenerative heat exchanger including a rotor, a conduit for passing hot exhaust gases from the driving motor to the heat exchanger, a conduit for passing cooled exhaust gases from the heat exchanger to the atmosphere, a conduit for passing air to be heated to the heat exchanger, conduit means for passing heated air from the heat exchanger to the radiators, a turbine positioned in the hot exhaust gas conduit, and gearing operatively connecting said turbine to said rotor. 90 95

3. In a motor driven vehicle, an internal combustion driving engine, a passenger body, radiators in said passenger body, a regenerative heat exchanger including a rotor, a conduit for passing hot exhaust gases from the driving motor to the heat exchanger, a conduit for passing cooled exhaust gases from the heat exchanger to the atmosphere, a conduit for passing air to be heated to the heat exchanger, conduit means for passing heated air from the heat exchanger to the radiators, a turbine positioned in the hot exhaust gas conduit, gearing operatively connecting said turbine to said rotor, and a fan 100 operatively connected to said engine and positioned in proximity to the entrance of the conduit for passing air to be heated to the heat ex- 105 110 115

changer.
